WASHING-MACHINE BENCH.

1,126,597.

Specification of Letters Patent.

Patented Jan. 26, 1915.

Application filed November 17, 1913. Serial No. 801,379.

To all whom it may concern:

Be it known that I, ORLA H. WATKINS, a citizen of the United States, and resident of Clinton, in the county of Clinton and State 5 of Iowa, have invented new and useful Improvements in Washing-Machine Benches, of which the following is a description, reference being had to the accompanying drawings, which are a part of this specification.

10 My invention has relation to improvements in washing machine benches.

The primary object of the invention is, to provide a device designed to be placed adjacent to a washing machine and its wringer 15 attachment, and adapted to handle tubs, such as rinsing or bluing tubs, and to place them in position under the wringer without having to lift these tubs, or to move the washing machine with its attached wringer.

20 A further object is to so construct said bench as to render the same capable of being folded and put away, thus requiring no more space than an ordinary ironing board.

With the above, and other incidental, objects in view, the invention consists of the 25 devices and parts, or the equivalents thereof, as hereinafter more fully set forth.

In the accompanying drawing, Figure 1 is a side elevation of the bench, parts broken 30 away, and showing in full line one adjustment of the top of the bench, and in dotted line another adjustment of said top. Fig. 2 is a bottom view of a fragment of the bench; Fig. 3 is a cross section on the line 3—3 of Fig. 1; and, Fig. 4 is a side elevation, on a 35 reduced scale, showing two tubs resting on the top of the bench, and showing in dotted line a washing machine and its attached wringer, in juxtaposition to the bench, one 40 of the said tubs being shown in full lines in proper position with respect to the wringer, and by dotted lines an adjustment of the top of the bench, so as to bring the tub first referred to out of its former alined position 45 with respect to the wringer, and the other tub in alined position with respect to said wringer.

Referring to the drawing, the numerals 5—5 indicate the side pieces, and 6—6 the 50 end pieces of a rectangular frame. The side pieces are of L-shaped form, with the horizontal members thereof extending inwardly toward each other, and the end pieces are flat straps which, at opposite ends, are con-

nected to the under side of the horizontal 55 members of the side pieces. The end pieces are further connected to the side pieces by means of diagonal brace straps 7, each end piece having two of said straps extending therefrom, and connecting with, the respective side pieces. The L-shaped side pieces 5 of the frame are also braced and connected by means of a central strap 8, which strap has its opposite ends bent upwardly at right angles and connected to the outer side of the 60 vertical members of the side pieces.

Pivoted to opposite ends of side pieces 5 of the frame, are pairs of legs 9—9. The two legs of each pair are braced and connected together by means of a brace strap 70 10. By pivoting the legs to opposite ends of the frame, said legs are thereby rendered capable of being swung or turned under the frame and top portion of the bench. In other words, the device is in that sense foldable, and can, therefore, be put away without requiring any more space than an ordinary ironing board.

The numeral 11 indicates the bench top. To the under side of this top are secured two 80 transverse blocks 12—12. Each of these blocks carries bearings 13—13 for a transverse shaft 14. Each shaft carries on opposite ends rollers 15—15, which are adapted to ride on the horizontal members or ledges 85 of the L-shaped side pieces 5 of the frame.

It is desirable that some means be provided for preventing the separation of the bench top from its supporting frame work, and for this purpose I secure to opposite 90 ends of each of the blocks 12, plates 16—16. Each of these plates is formed with depending angular extensions, as clearly shown in the drawing, the horizontal members of said extensions passing beneath the horizontal 95 ledges of the L-shaped side members 5 of the frame. By the provision of these L-shaped stops 16, it is evident, that upon an up movement of the bench top 11, the horizontal members of said stops will come in contact 100 with the under side of the horizontal ledges of the side pieces of the frame, and, consequently, withdrawal or separation of the bench top from the frame upwardly is prevented. The stops 16 also act as a means for 105 preventing the separation of the bench top longitudinally from the frame, and likewise serve to limit the movement longitudinally

in either direction of the bench top, by reason of the contact of one set of the stops 16 with the diagonal straps 7 at one end of the frame, or, the contact of the two stops 16 of the other set with the diagonal straps 7 at the opposite end of the frame. In Figs. 1 and 2 of the drawing, the stops 16 at the left hand end are shown in contact with the left hand diagonal brace straps 7, thus showing that the bench top is adjusted or slid toward the left to its full extent. In Fig. 1 of the drawing, in dotted lines, the bench top is shown as adjusted toward the right to its full extent, the other two stops 16 being in contact with the right hand diagonal straps 7.

On one of its side edges, and centrally, or approximately central, thereof, the bench top is formed with a rounded recess 17. This recess is for the accommodation of the limb of the person operating the device, and permits such person to obtain more ready access to the tubs and to the wringer. Also adjacent one longitudinal edge of the bench top, and secured to the under side thereof, is preferably employed a longitudinal brace or reinforcing strip 18.

In Fig. 4 of the drawing, I show in dotted lines the outline of a washing machine, indicated by the numeral 19, and by dotted lines the outline of a wringer 20 attached to or carried by said machine. The washing machine and its attached wringer are shown as arranged adjacent to that side of the bench top which is unprovided with the recess 17, and the said bench top is shown as supporting two tubs 21 and 22 respectively. It will be assumed that the bench top is adjusted to the position shown in Fig. 4 of the drawing, that is to say, is adjusted to its full extent toward the left, and that also said top is supporting the two tubs 21 and 22, with the tub 21 alined with the wringer, said tub 21 being the rinsing tub and the tub 22 the bluing tub. It will be further assumed that the clothes are being taken from the washing machine and are being passed through the wringer rolls for deposit in the rinsing tub. After the clothes are thus deposited in the rinsing tub they are left therein for the proper time to insure thorough rinsing. They are then taken by hand and passed through the wringer rolls, so as to be thoroughly wrung out, and

are then deposited in the bluing tub 22. The bench top is now pushed to the right to the full extent permitted, the said top rolling on the rollers 15 during such movement. This adjustment of the bench top will bring the bluing tub 22 in alinement with the wringer. After the clothes have remained in the bluing tub for the requisite length of time, they are lifted therefrom and again passed through the wringer rolls, the said wringer rolls being then rotated in a direction to cause the clothes to travel over the washing machine to a place of deposit.

From the foregoing description, it will be seen that I provide a most desirable and efficient device to be used in connection with a washing machine and its wringer, the said device being adapted to handle the tubs and place them in position under the wringer without the necessity for lifting a tub or moving the machine.

What I claim is:

1. In a washing machine bench, the combination with a framework, of a supporting top longitudinally slidable on the framework, and means for limiting the sliding movement of the top in opposite directions.
2. In a washing machine bench, the combination of a framework, a supporting top longitudinally slidable on the framework, and means for preventing the upward separation of the top from the framework.
3. In a washing machine bench, the combination of a framework, a supporting top longitudinally slidable in said framework, brackets depending from the under side of the top, said brackets being in angular form, with the horizontal members thereof extending beneath the side members of the frame, whereby upward separation of the top from the framework is prevented, stops at opposite ends of the framework with which stops said brackets are adapted to contact, when the top is moved longitudinally in either direction, whereby the extent of the longitudinal movement of the top in opposite directions is regulated.

In testimony whereof, I affix my signature, in presence of two witnesses.

ORLA H. WATKINS.

Witnesses:

A. H. PADDICK,
ANETA RASMUSSEN.
